FIBER SPINNING METHOD AND APPARATUS

David E. O'Connor, Needham, Mass.

Application October 2, 1948, Serial No. 52,545

11 Claims. (Cl. 18—2.6)

1

This invention relates to improvements in fiber-spinning methods and apparatus wherein centrifugal force is utilized to convert viscous liquid and semi-liquid substances to a fibrous state. More particularly, it relates to an improved method and apparatus whereby various organic and inorganic viscous substances more effectively and efficiently may be converted to fiber on a commercially practicable scale, as compared with prior comparable fiber-spinning procedures. For example, the invention has a particular utility in the manufacture of mineral wool and glass wool fibers, and fibers made from chemical asbestos, and from various organic and artificial resins. While it will be described herein primarily in its adaptation for rock wool manufacture, it should be understood that the features of invention novelty will be found to have general utility wherever a viscous substance is to be converted to fiber as a result of a centrifugal throwing of globules of the substance from a swiftly rotating spinner member.

Mineral wool fibers, rock wool fibers, and other fibers of the general class to which the invention relates, customarily are produced commercially by directing a blast of air or steam across the direction of a vertical stream of the viscous substance which is to be converted to fiber. Ordinarily the viscous substance is in a molten state, delivering by gravity from a cupola, an electric furnace, or a glass tank. The blast of air or steam breaks the molten stream into discrete particles or globules, and drives the individual globules through space at high velocity with a resulting stringing out of the globules and ultimate solidifying of the fibers as they cool. The diameter and length of the fibers may be determined to some extent, by variation of the force of the blast which in turn will vary the speed of travel of the globules and the distance a globule will travel before solidifying. However, it has been practically impossible to attain complete fiberization of the globules. Rather, a solidified head or "shot" usually remains unfiberized at the leading end of each fiber, and these "shot" are a source of considerable annoyance and trouble in that they add considerably to the weight of any given mass of fiber without serving any useful purpose. Substantial expense and trouble is incurred to separate the "shot" from the fiber.

The mentioned air or steam blast procedure for producing fibers has the advantage that it is adaptable to the production of fiber on a commercially practicable scale. But use of either

2

air or steam requires equipment which is expensive to install and expensive to operate. In an air blast installation having a production capacity of one ton per hour, for example, an air compressor of the required capacity needs a one hundred horse power electric motor to drive it. A steam blast installation of the same production capacity requires a high pressure steam boiler approximating one hundred boiler horse power.

10 The initial cost of such equipment is high, and operating costs are high.

Efforts directed toward reduction of initial and operating costs of fiber-producing equipment have resulted in numerous proposals which utilize 15 centrifugal force to convert a viscous substance to a fiber state as a result of a centrifugal throwing of globules of the substance through space with high velocity. This so-called fiber-spinning process has met with only limited success principally 20 because any prior spinner member of commercially practicable size has been too limited in fiber-producing capacity. The process employs a spinner member which is relatively inexpensive to install and to operate, and it is effective as a 25 fiberizing procedure, although it has not materially reduced the amount of "shot" in any given mass of fiber, as compared with the air and steam blast procedures.

However, fiber produced by the centrifugal 30 spinning process generally may be superior in quality to the fiber produced by the air or steam blast process, in that the blast process fiber inherently is more brittle and fragile. When a blast of air or steam strikes a stream of molten material, the molten material suddenly is substantially reduced in temperature which not only reduces the capacity of each globule to be completely fiberized before solidification occurs, but effects a tempering of the material whereby the 35 subsequently formed fiber has a brittleness and fragility which it would not have if not subjected to the sudden substantial temperature drop. In the centrifugal spinning process, on the other hand, the spinner member may have operating 40 temperature not greatly below the temperature of the molten substance which is delivered to the spinner, and the centrifugally thrown globules are subjected to a gradual cooling as they fly through the surrounding atmosphere. They thus 45 are better conditioned for a more complete fiberization of each globule, and the resulting fibers are more resilient and flexible, as compared with the blast-produced fibers.

However, the various advantageous aspects attaching to the centrifugal spinner process have

not been satisfactorily available for any large scale commercial utilization because of the earlier mentioned limitations as regards productive capacity.

It is among the objects of my present invention to substantially increase the efficiency and productive capacity of fiber-producing centrifugal spinner mechanisms, as compared with prior comparable mechanisms of like size. I provide a method and means whereby a continuous supply of a viscous substance which is to be converted to fiber is positively separated on a spinner member into multiple generally radially directed individual streams of globules, and each globule moving outward to the periphery of the spinner member without appreciable angular slippage between the substance and the spinner member. As a result, the practicable speed of the spinner member may be increased substantially, as compared with practicable speeds of prior comparable mechanisms, with assurance that each globule which is ready to be thrown into space will have an angular speed equal to the peripheral speed of the spinner member.

Another object is to provide a centrifugal fiber-producing method and apparatus having provision for ensuring an approximate uniformity of size of the globules of a viscous substance which are thrown centrifugally from a spinner member. Means spaced at intervals around the peripheral portion of the spinner member provide radial walls defining radial passageways leading to the periphery of the spinner member, and the inner ends of the radial walls sever approximately uniform globule-quantities of the viscous substance from the supply quantity on the spinner member inward of the radial walls, whereby the globules travelling outward between the radial walls have approximately uniform size.

A further object is to provide a centrifugal fiber-producing method and apparatus wherein a viscous substance which is to be converted to fiber is thrown into space from surfaces disposed generally at right angles to the plane of rotation of the spinner member.

It is, moreover, my purpose and object generally to improve upon prior methods and apparatus for producing fiber and more especially for increasing the efficiency and productive capacity of centrifugal fiber-spinning mechanisms.

In the accompanying drawings:

Fig. 1 is a side elevation of a centrifugal fiber-spinning apparatus embodying features of my invention;

Fig. 2 is a top plan view of the apparatus of Fig. 1, including a diagrammatic representation suggestive of the fiber-producing effect of the apparatus;

Figs. 3, 4, and 5 are top plan views of modified forms of spinner members, a portion of the spinner member in Fig. 5 being broken away;

Fig. 6 is a fragmentary top plan view of another modified form of spinner member;

Fig. 7 is a fragmentary top plan view of still another modification;

Fig. 8 is a cross-sectional view on line 8-8 of Fig. 6;

Fig. 9 is a cross-sectional view on line 9-9 of Fig. 7;

Fig. 10 is a medial cross-sectional view of a sectional form of spinner member; and

Fig. 11 is a medial cross-sectional view of a further modified form of spinner member.

Referring to Figs. 1 and 2 of the drawings, the

particular embodiment therein shown has a spinner member 10 fixed on the upper end of a shaft 12 which latter is journalled in suitable bearings 14 on spaced supporting elements 16. If desired, the shaft 12, bearings 14 and supporting elements 16 may have associated with them any suitable means for maintaining them at satisfactorily low operating temperatures, such as air or water jackets (not shown). The spinner member 10 may be driven in any convenient manner, such as through the bevel gears 18, 20, from any available and suitable source of power.

The spinner member 10 may be generally a flat disk but, according to the invention, a series of upstanding vanes 22 are equally spaced apart around the peripheral margin of the disk. The vanes are rigid on the upper face of the disk and, in the form of Figs. 1 and 2, they have radial extent from its periphery inward a distance approximating one fourth of the radius of the disk. However, the radial length of the vanes may be varied to suit particular requirements, and the shape and directions of extent of the vanes may be selected to suit the requirements of any particular installation of any particular run of fiber, as suggested in the modifications of Figs. 3-6 of the drawings.

The spinner member or disk 10 is driven at high speed, and viscous material which is to be converted to fiber is deposited in a continuous stream on the upper face of the disk, inward of the vanes 22. Ordinarily the material to be converted will be in a molten state and may be flowed to disk 10 along an inclined trough 24 or the like delivery device from a source of supply, such as a cupola, an electric furnace, a glass tank, or the like. The stream of viscous material delivers to the swiftly rotating disk 10 at a location preferably at the center of the disk or to one side of its axis and between the axis and the circle of the inner ends of vanes 22, and the deposited material moves outward on the disk by centrifugal force. Inasmuch as the deposited material inward of the vanes 22 can slip on the disk as the disk rotates at high speed, the portions of the outwardly moving material reaching the inner ends of the vanes 22 become engaged by the swiftly and positively moving inner ends of the vanes which act as knives for severing approximately uniform globule-quantities from the supply, and these globule-quantities enter between adjacent blades and each moves outward as a globule toward the periphery of the disk 10. Each globule moves outward on one of the blades 22 and is positively carried around the disk axis by the blade without possibility of angular slippage. Hence, each globule which is about to leave the periphery of the disk will have angular speed equal to the peripheral speed of the disk.

Heretofore, so far as I am aware, friction between the spinner members and the viscous material has been relied upon to induce angular travel of the material around the disk axis. Angular slippage between the disk and the material has reduced the angular speed of the material reaching the periphery of the disk substantially below the peripheral speed of the disk. Also, there has been no control heretofore tending toward uniformity of size of globules leaving the spinner members. In contrast, my improved vaned spinner member ensures utilization of the full available forces for propelling each thrown globule on its course through space, and the cutting action of the inner ends of the vanes 22

ensures a more general uniformity of size of departing globules.

It will be apparent that the vanes 22 positively carry the globules, or other quantities of the molten material, banked against them, around the disk axis at an angular speed equal to the speed of the disk and regardless of what that disk speed may be. Hence the disk speed may be substantially increased above the speeds heretofore practicable with a corresponding increase in the fiber-producing capacity of any particular size of unit. Heretofore, any increase of speed of a spinner member greatly increased the mentioned angular slippage, and practicable speeds have been such that production capacity has been impractically low for large scale fiber production.

The diagrammatic representation of the viscous material in Fig. 2 should not be regarded as an actual condition but is suggestive of what is believed to be the general course of the deposited viscous material under the combined influence of rotation of the disk 10, centrifugal force and the vanes 22. It has been determined in actual operation of the spinner disk that the globules are discharged from the spinner disk around the entire periphery when the viscous material is deposited at any location on the spinner disk inside of the inner ends of the vanes. It has been determined that when the viscous material is deposited on the sloped inner ends of the vanes 22 shown in Fig. 11 the globules are discharged from the disk periphery through a relatively small arc of the disk periphery. In Fig. 11 the inner ends of the vanes 22 are inclined from the vertical sloped downwardly towards the disk axis and the outer ends of the vanes 22 are approximately parallel to the inner ends of said vanes.

In addition to the increased productive capacity attainable as a result of the permissible greater speed of my vaned spinner member 10, and the greater propulsive forces which are active for dispatching globules through space, it is important to note also the consequent improved nature of the ultimate fibers. The spinner disk preferably will be made of high melting temperature material, such as chrome-nickel-iron alloy, so that it may be maintained at a temperature not greatly less than that of the molten material delivering to it. This avoids any sudden substantial drop in temperature of the material arriving on and travelling outward to the periphery of disk 10. The temperature of the spinner disk may be maintained by the application of heat by any conventional means not shown such as a gas burner firing downward and directed at the top of the disk or electric heating elements incorporated in the underside of the disk to which electric current is fed by brushes, or any other suitable method. The departure of a globule from the disk into space subjects the globule to the temperature of the surrounding atmosphere which will have higher temperature around the disk, gradually diminishing outwardly from the disk. The globules become cooled more gradually to their temperature of solidification than is the case with air and steam blast processes, and the fibers are less brittle and fragile as compared with the product of the blast processes. Also, as the globules are dispatched from my vaned disk, without being subjected to sudden substantial temperature drop, they are in better condition to string out into fiber, and they can become completely converted to fiber because propelled by

greater forces through greater distances before solidification, as compared with prior centrifugal fiber-producing procedures.

As illustrated in Figs. 3-5, the vanes may be variously shaped and positioned on the spinner member 10, and may have various lengths from the periphery of the member inward toward the axis of rotation. Figs. 3 and 4 disclose an embodiment wherein each of the vanes is positioned in angular relation to the adjacently positioned vanes, and Fig. 5 discloses the use of arcuate-shaped vanes. Also, if desired, the portion inward of the vanes may be dished as at 26 in Figs. 9 and 10 to receive therein a suitable refractory material 27 on which the molten material is deposited. This reduces erosion of the wheel due to action of the molten material.

The Figs. 6 and 8 form has a broad marginal flange 28 through which radial passages 30 extend. In this case the lagging side wall of each passage acts on the viscous material the same as the vanes in the other illustrated forms.

In Fig. 10 there is shown a sectional form of spinner member which has the commercial advantage that the parts with which the molten material comes in contact readily may be replaced when desired without discarding the main body portion of the spinner member. The vanes 22, in this form, are on a ring element 32 which is removably bolted or screwed at 34 to a body disk 36. A disk 27 of refractory material removably covers the central region of the body disk 36 and may be secured in any suitable manner as by being clamped under the inner projecting ends 40 of the vanes 22. Deterioration of the refractory disk 27 and/or the ring element 32 quickly may be remedied by replacing them with new ones on the body disk 36. In Fig. 11 a form of spinner member is shown wherein the vanes 22 have their inner ends inclined in obtuse angular relation to the flat surface of the spinner member.

While I have shown particular embodiments of my invention which presently are considered preferred embodiments, it should be understood that the axis of the spinner member may, if desired, be variously inclined from the illustrated vertical position, and that the upstanding walls of the vanes 22 and passages 30 may be variously inclined with respect to the plane of the spinner member.

I claim:

1. Apparatus for producing fiber comprising a spinner member mounted for rotation at relatively high speeds about a vertical axis, and having a flat central portion adjacent its axis, a spout for depositing viscous material on said spinner member at its flat central portion, whereby the deposited material travels outwardly on said member toward the periphery thereof under the urge of centrifugal force simultaneously with attainment of an angular velocity in the direction of rotation of the spinner member, abutment means on the spinner member arranged and adapted to divide said deposited substance into separated outwardly moving portions, each said abutment extending above the plane of said spinner member from adjacent its flat central portion about the periphery of the spinner member and maintaining said outwardly moving portion of the material against angular slippage on said spinner member, whereby said material reaching the periphery of the spinner member may be thrown therefrom at an angular speed equal to the peripheral speed of said member, and

a removable body of refractory material on said spinner member constituting the flat central portion thereof and providing the surface on which said viscous material is deposited.

2. Apparatus for producing fiber comprising a spinner member mounted for rotation at relatively high speeds about a vertical axis, and having a flat central portion adjacent its axis, a spout for depositing viscous material on said spinner member at its flat central portion, whereby the deposited material travels outwardly on said member toward the periphery thereof under the urge of centrifugal force simultaneously with attainment of an angular velocity in the direction of rotation of the spinner member, abutment means on the spinner member arranged and adapted to divide said deposited substance into separated outwardly moving portions, each said abutment extending above the plane of said spinner member from adjacent its flat central portion about the periphery of the spinner member and maintaining said outwardly moving portion of the material against angular slippage on said spinner member, whereby said material reaching the periphery of the spinner member may be thrown therefrom at an angular speed equal to the peripheral speed of said member, said spinner member comprising a spinner body and having means for removably securing said abutment means to the spinner body.

3. In apparatus for producing fibers from viscous material, the combination comprising a circular-shaped spinner member mounted for rotation about its axis at relatively high speed in a substantially horizontal plane, said spinner member having a substantially flat upper surface provided with a plurality of passageways defined by a plurality of upstanding walls positioned in spaced relation about the peripheral edge of said surface and extending inwardly therefrom a portion only of the distance to the axis of the spinner member, and a delivery device constructed and arranged to deposit said viscous material upon the surface of said spinner member between its axis and the inner ends of said walls.

4. In apparatus for producing fibers from viscous material, the combination comprising a circular-shaped spinner member mounted for rotation about its axis at relatively high speeds in a substantially horizontal plane, said spinner member having a substantially flat upper surface provided with a plurality of upstanding vanes spaced about the peripheral edge of said surface and extending therefrom inwardly a portion only of the distance to the axis of the spinner member, and a delivery device constructed and arranged to deposit said viscous material upon the surface of said spinner member between its axis and the inner ends of said vanes.

5. In apparatus for producing fibers from viscous material, the combination comprising a circular-shaped spinner member mounted for rotation about its axis at relatively high speeds in a substantially horizontal plane, said spinner member having a substantially flat upper surface provided with a plurality of upstanding radially extending vanes spaced about the peripheral edge of said surface and extending therefrom inwardly a portion only of the distance to the axis of the spinner member, and a delivery device constructed and arranged to deposit said viscous material upon the surface of said spinner member between its axis and the inner ends of said vane.

6. In apparatus for producing fibers from vis-

cous material, the combination comprising a circular-shaped spinner member mounted for rotation about its axis at relatively high speeds in a substantially horizontal plane, said spinner

5 member having a substantially flat upper surface provided with a plurality of upstanding vanes spaced about the peripheral edge of said surface, each of which extends therefrom inwardly a portion only of the distance to the axis of the spinner member in angular relation to the adjacently positioned vanes, and a delivery device constructed and arranged to deposit said viscous material upon the surface of said spinner member between its axis and the inner ends of said vanes.

7. In apparatus for producing fibers from viscous material, the combination comprising a circular-shaped spinner member mounted for rotation about its axis at relatively high speeds in a substantially horizontal plane, said spinner member having a substantially flat upper surface provided with a plurality of upstanding arcuately shaped vanes spaced about the peripheral edge of said surface and extending therefrom inwardly a portion only of the distance to the axis of the spinner member, and a delivery device constructed and arranged to deposit said viscous material upon the surface of said spinner member between its axis and the inner ends of said vanes.

8. In apparatus for producing fibers from viscous material, the combination comprising a circular-shaped spinner member mounted for rotation about its axis at relatively high speeds in a substantially horizontal plane, said spinner member having a substantially flat upper surface provided with a plurality of upstanding vanes spaced about the peripheral edge of said surface and extending therefrom inwardly a portion only of the distance to the axis of the spinner member, each of said vanes having its inner end inclined in obtuse angular relation to the flat upper surface of said spinner member, and a delivery device constructed and arranged to deposit said viscous material upon the surface of said spinner member between its axis and the inner ends of said vanes.

9. The method of converting semi-liquid viscous substance into fibers, which consists of depositing said semi-liquid viscous substance upon a flat surface of a rapidly rotating circular-shaped spinner member provided with a plurality of spaced vanes upstanding from the surface thereof, which vanes extend from the periphery of the spinner member inwardly toward but short of the axis thereof, said semi-liquid viscous substance being deposited between the inner ends of the vanes and the axis of the spinner member, the rotational speed of the spinner member being such that the semi-liquid viscous material is moved toward the periphery of the surface by centrifugal force and is divided into separated portions which are restrained against appreciable angular slippage on the surface by the spaced vanes until formed into fibers by being thrown centrifugally from the rotating surface at an angular speed equal to the peripheral speed of said spinner member.

10. The method of converting molten material into fibers, which consists of depositing said molten material upon a flat surface of a circular-shaped spinner member rapidly rotating about a vertical axis, which surface is provided with a plurality of spaced vanes upstanding from the surface thereof that extend from the pe-

periphery of the spinner member inwardly toward but short of the axis thereof, said molten material being deposited between the inner ends of the vanes and the axis of the spinner member, the rotational speed of the spinner member being such that the molten material is caused to travel outwardly to the periphery of the spinner member under the influence of centrifugal force and to be divided into separated portions which are held by the vanes against appreciable angular slippage on the spinner member until thrown off centrifugally from the edge of said spinner member at an angular speed equal to the peripheral speed of said spinner member.

11. The method of producing fibers which consists of flowing a continuous stream of semi-liquid viscous material onto a rapidly rotating flat surface of a disk provided with a plurality of spaced vanes upstanding from said surface, which vanes extend from the periphery of said disk inwardly toward but short of the axis thereof, said stream of semi-liquid viscous material being flowed onto said disk surface between the inner ends of the vanes and the axis of the disk,

whereby the material is caused by centrifugal force to travel outwardly to the periphery of the disk and to be divided into separate portions which are held by said vanes against appreciable angular slippage on the disk surface until thrown off centrifugally from the disk at an angular speed equal to the peripheral speed of the disk.
